UNITED STATES PATENT OFFICE.

EDWARD C. KAHN, OF MILWAUKEE, WISCONSIN.

LIQUID-FUEL BURNER.

1,254,507.

Specification of Letters Patent. Patented Jan. 22, 1918.

Application filed February 5, 1917. Serial No. 146,586.

To all whom it may concern:

Be it known that I, EDWARD C. KAHN, a citizen of the United States, and resident of Milwaukee, in the county of Milwaukee and State of Wisconsin, have invented certain new and useful Improvements in Liquid-Fuel Burners; and I do hereby declare that the following is a full, clear, and exact description thereof.

10 My invention relates to new and useful improvements in liquid fuel burners, more particularly of that type including a burner head provided with a multiplicity of jet openings and having disposed there adjacent a vaporizing chamber adapted to receive heat from the jets of the burner head.

It is in general the object of my invention to simplify the structure and to increase the efficiency of burners of this nature.

20 More specifically it is an object of my invention to provide a burner head having its jet apertures so arranged with respect to the supply passages thereof as to prevent the possibility of the occurrence of combustion within the burner head, it being more specifically an object to effect this result by providing for a comparatively rapid flow of fuel gas immediately adjacent the jet apertures.

30 A further important object resides in the provision of a vaporizing chamber associated with the burner head in such manner as to procure an efficient vaporizing heat therefrom, and wherein means is provided for preventing a too great heat of the vaporizing chamber which might result in melting the walls thereof.

40 A further object resides in the provision of a burner head and vaporizing chamber so disposed as to provide for the passage of air there-between in such manner as to insure a proper combustion at the outer-most jet apertures to prevent possible escape of unburned gas and to prevent the occurrence of soot.

45 A further object resides in the provision of an exceedingly compact general assembly of the burner head vaporizing chamber and associated parts whereby the entire burner 50 may be supported by the fuel supply pipe thereof.

55 A more detailed object resides in the provision of an expansion chamber immediately adjacent the inlet mouth of the vaporizing

chamber whereby to provide for precipitation of possible sediment contained in the fuel, and further whereby to prevent an excessive supply of fuel to the vaporizing chamber which might result in flooding said chamber.

60 A further object resides in the provision of a means associated with the vapor discharge nozzle of the burner for cleaning out the nozzle should it become clogged.

65 With the above and other objects and advantages in view the invention resides more particularly in the novel combination, formation and arrangement of parts hereinafter described and pointed out in the appended claims.

70 In the drawings:

Figure 1 is a vertical sectional view through the entire burner, the plane of this view with respect to the fuel expansion chamber being indicated by the line 1—1 of Fig. 3.

75 Fig. 2 is a fragmentary horizontal sectional view through one side portion of the burner on the line 2—2 of Fig. 1.

Fig. 3 is an elevational view of the fuel expansion chamber.

80 Fig. 4 is a detail sectional view through the nozzle cleaning mechanism on the line 4—4 of Fig. 1.

85 Referring now more particularly to the accompanying drawings, 5 designates the upstanding supply pipe of the burner, and this supply pipe is threaded in one end of an obtuse elbow section 6, and this elbow section is connected by preferably integral bars 7 90 with an acute elbow section 8 having threaded in its up-standing end the vapor discharge nozzle 9 and connected at its other end by a suitable coupling 10 with a vapor pipe 11 extending from the vaporizing 95 chamber. Also threaded on the upper end of the acute elbow section 8 is the lower portion of a skeleton cage 12, having an upper reduced neck portion receiving the lower end of a mixing tube 13 which has its upper end 100 engageable in a nipple 14 depending from a circular plate 15 which forms the bottom of the burner head. This plate is provided with a relatively narrow upstanding peripheral flange 16 and seated on this flange is the 105 peripheral edge of a plate 17 forming the top of the burner head. The plates are held together by rivets 18 passed through their

intermediate portions and these rivets are shouldered as shown to provide for an exact spaced relation of the intermediate plate portions.

5 The vaporizing chamber comprises an annular casing 19 having its side walls inclined inwardly in parallel relation, and the interior diameter of the lower portion of the casing is slightly greater than the exterior diameter of the burner head, while the diameter of the upper portion of the casing is less than the diameter of the burner head whereby to overhang the burner head and thus intersect the axes of the outermost 10 jet apertures of the burner head which, as will be later described, are disposed at the peripheral portion of its top. The inner wall of the vaporizing chamber is projected vertically downward to form an annular 15 apron 20 disposed in spaced relation about the burner head to thus define an annular air inlet passage there-between, and the burner head and vaporizing chamber are connected by bolts passed through said 20 apron and through down-turned peripheral ears 21 on the top plate 17 of the burner head. The apron 20 has also secured thereto 25 hanger arms 22 which support an annular trough 23 adapted to receive a suitable fuel 30 fluid for initially heating the burner to start its operation.

Depending from one side of the vaporizing chamber 19 is a fuel expansion chamber 24 which is decidedly oblong in shape at its 35 upper portion, and which is taperingly decreased in length and taperingly increased in width toward its lower end to merge into a nipple section 25 receiving a coupling nipple 26 which is suitably connected by the 40 coupling 27 with the upper end of a pipe 28 which has its lower end connected by a coupling 29 with the upper end of the obtuse elbow section 6 which is carried on the main supply pipe 5. The vapor pipe 11 45 extending from the elbow casting is connected at its upper end by a similar coupling 30 and nipple 31 with a depending nipple enlargement 32 of that portion of the vaporizing chamber which is diametrically opposed to the expansion chamber 24.

Thus the fuel passes from the supply and supporting pipe 5 into the expansion chamber 24 from whence it is branched to extend to the sides of the vaporizing chamber, 55 and these branch streams of fuel which are vaporized upon their passage through the chamber are united at the nipple enlargement 32 and pass downwardly through the pipe 11 and the elbow section 8 and are 60 discharged from the nozzle 9, drawing sufficient air into the mixing tube 13 to insure proper ignition. The expansion chamber 24 provides for the precipitation of possible sediment in the fuel, and also provides for 65 the storage of an auxiliary quantity of fuel

whereby a continuous and uniform flow through the vaporizing chamber is provided and also prevents flooding of the vaporizing chamber by the fuel.

Concentric staggered series of jet apertures 33 are provided in the peripheral portion of the top plate 17 of the burner head, the outermost axes of these apertures, as stated, intersecting the inner wall of the vaporizing chamber. Thus an annular bed 70 of apertures is provided, which is of a width equal to substantially one-fifth the diameter of the burner head. Immediately inwardly of the bed of jet apertures, the top plate is provided with an annular upwardly inclined 75 portion whereby the central portion of the plate is upwardly offset to such extent that the height of the chamber defined by the plates of the burner head is substantially doubled at its central portion. By this arrangement, an accelerated flow of fuel vapor is procured immediately adjacent the jet apertures to prevent possible back-fire which would cause combustion within the burner head, experience having demonstrated that 80 the occurrence of such combustion creates a heat sufficient to melt the burner head. It is noted that the pressure and consequently 85 the velocity of the fuel vapor tends to decrease as it moves outwardly into the head 90 due to passage through successively increasing circumferential areas. In my improved construction, however, this action is counteracted by decreasing the height of the chamber, to thus reduce the circumferential passage areas of the vapor immediately in advance of the jet apertures. As the vapor moves past the inner jet apertures, its pressure, and consequently its velocity tends to 95 increase due to the re-heating effected by 100 the jets.

Returning now to the vaporizing chamber, it is noted that the chamber is shielded to some extent by the annular film of air flowing between the apron 20 of the chamber and the burner head. When the burner is operating at a relatively low heat, the volume of air drawn through this annular passage by the flames is considerably less than the volume of air drawn therethrough 110 incidental to operation of the burner at a relatively high heat. Thus, an automatic control is provided for preventing an excessive over-heating of the vaporizing chamber which might melt it, while at the same 115 time a sufficient vaporizing heat is at all times assured due to the intersection of the inner wall thereof by the outermost jet aperture axes. By providing a vaporizing chamber which is upwardly elongated in cross 120 section and inclining both of its side walls inwardly, a proper heating of all portions of the fuel passing therethrough is insured.

The annular current of air passing between the vaporizing chamber and burner 125

head, in addition to its function of preventing excessive heating of the chamber also serves to exert a lateral pressure on the vapor emerging from the outermost jet apertures whereby to direct said vapor inwardly toward the body of the flame and prevent possible escape of unignited gas. Also by supplying a sufficiency of oxygen at the outermost and consequently the coolest portion of the body of the flame, the occurrence of soot is prevented.

To provide a device for cleaning the needle passage of the nozzle plug 9, the angle portion of the elbow section 8 is enlarged to provide a chamber 34 which is closed at one end by a cap 35 threaded thereto, and which has its opposite wall elongated to form a bearing for the shaft 36 having an operating handle 37 on its outer end, and having a plate 38 on its inner end to which is eccentrically pivoted an arm 39 terminating in a needle section disposed in the passage of the nozzle plug. This passage, to provide for a maximum cleaning thereof is taperingly decreased in width from its lower end to a point immediately adjacent its upper end. Thus by swinging the arm 37, the needle will be projected through the upper end of the passage to clear it of any possible obstructions. The arm is normally urged to its retracted position by the weight of the operating arm 37. For procuring a tight engagement of the plate 38 with the adjacent end of the chamber 34, an expansile spring 40 is disposed in the chamber and bears against said plate and against the closure cap 35.

Attention is directed to the mutual supporting relation of the various parts of my improved burner whereby the entire burner is supported upon the supply pipe 5, it being noted that the mutually connected burner head and surrounding vaporizing chamber are supported on the single elbow casting, both by the pipes 11 and 28, and by the mixing tube 13.

While I have shown and described a preferred embodiment of my invention, it is obvious that to meet differing conditions of use, various modifications of structure may be resorted to without departing in any manner from the spirit of the invention or exceeding the scope of the appended claims.

What is claimed:

55 1. In a fluid fuel burner, a burner head comprising a circular bottom plate provided centrally with an inlet port, a top plate disposed in spaced relation thereabove, an annular bed of vertically extending jet apertures in the peripheral portion of the top plate and the central portion of one of the plates being outwardly offset whereby to increase the height of the chamber defined by said plates.

60 2. In a fluid fuel burner, a burner head

including a bottom plate provided with a central inlet port, a top plate spaced therefrom and provided with an annular bed of vertically extending jet apertures in its peripheral portion, and that portion of the top plate immediately inwardly of said jet apertures being inclined upwardly whereby the central portion of the plate is upwardly offset.

3. In a fluid fuel burner, a burner head comprising a circular bottom plate provided centrally with an inlet port, a top plate disposed in spaced relation thereabove, an annular bed of vertically extending jet apertures in the peripheral portion of the top plate and the central portion of one of the plates being outwardly offset whereby to increase the height of the chamber defined by said plates, and said offset plate portion being parallel throughout with the other central plate portion whereby to define uniformly successively increasing circumferential areas of passage.

4. A fluid fuel burner comprising a circular burner head having vertically extending jet apertures, an annular vaporizing chamber disposed about the burner head and having its inner wall inclined inwardly to intersect the axes of the outermost apertures, and an annular apron depending from the vaporizing chamber whereby to form in conjunction with the peripheral wall of the burner head an air inlet passage.

5. In a fluid fuel burner, a pair of connected elbow sections, said sections comprising an obtuse elbow section and an acute elbow section, a supply pipe connected with one of said sections, a burner head, a mixing tube connected with the burner head and one of the elbow sections, a vaporizing chamber disposed adjacent the burner head and connected therewith, a fuel pipe connecting the vaporizing chamber and the elbow section connected with the supply pipe, a vapor pipe connecting the other elbow section and vaporizing chamber, and said pipes serving to support the burner head and vaporizing chamber upon the elbow sections.

6. A fluid fuel burner, comprising a burner head, and a vaporizing chamber there-adjacent having its inner wall inclined inwardly to intersect the axis of the outermost portion of flame from said burner head, an inlet for said chamber, and an outlet opposite said inlet, said chamber being increased in size at said inlet, substantially as described.

7. In a fluid fuel burner, a pair of connected elbow sections comprising an obtuse elbow section and an acute elbow section, a supply pipe connected with the obtuse elbow section, a burner head, a mixing tube connected with the burner head and the acute elbow section, a vaporizing chamber disposed adjacent the burner head, a pipe con-

nection between said obtuse elbow section and the vaporizing chamber, a vapor pipe connecting said acute elbow section and the vaporizing chamber, and controlling means carried by said acute elbow section, substantially as described.

In testimony that I claim the foregoing I

have hereunto set my hand at Milwaukee, in the county of Milwaukee and State of Wisconsin, in the presence of two witnesses. 10
